UNITED STATES PATENT OFFICE.

HOWARD S. CRISPIN, OF THERMOPOLIS, WYOMING.

GOVERNOR FOR WATER-DRIVEN MOTORS.

1,406,936.

Specification of Letters Patent. Patented Feb. 14, 1922.

Application filed March 29, 1920. Serial No. 369,612.

To all whom it may concern:

Be it known that I, HOWARD S. CRISPIN, a citizen of the United States, residing at Thermopolis, in the county of Hot Springs 5 and State of Wyoming, have invented certain new and useful Improvements in a Governor for Water-Driven Motors, of which the following is a specification.

This invention relates to devices for controlling the speed of water driven motors, such as water wheels and the like, and has for one of its objects to simplify and improve the construction and increase the efficiency and utility of devices of this character.

Another object of the invention is to provide a device of this character including a water driven motor, flow controlling means, electrically operated means for actuating the flow controlling means, a governor operative by the motor, and means whereby the speed of the motor controls the flow controlling means.

With these and other objects in view, the invention consists in certain novel features of construction as hereinafter shown and described and then specifically pointed out in the claims, and in the drawings illustrative of the preferred embodiment of the invention.

Figure 1 is an elevation partly in section, of the improved device.

Figure 2 is a plan view of the parts shown in Figure 1.

Figure 3 is an enlarged sectional detail on the line 3—3 of Figure 1 looking in the direction of the arrow.

Figure 4 is an enlarged sectional detail on the line 4—4 of Figure 1.

The improved device may be applied without material structural change to water driven motors and the flow controlling means associated therewith, of any of the various forms in use, and it is not desired 45 to limit the invention in any manner in this respect, but for the purpose of illustration a conventional motor of the turbine type, represented as a whole at 10, and a conventional flow controlling mechanism 50 represented as a whole at 11. The intake conduit is represented at 12, the discharge or "tail" conduit at 13.

The drive shaft of the motor is represented at 15 and includes a belt pulley 16.

55 A governor device is located adjacent the belt pulley and includes a sleeve 17, a belt

pulley 18 rotative on the sleeve and around which a belt 19 from the pulley 16 on the motor shaft 15 operates. The governor likewise includes a drive shaft 20 slidable 60 through the sleeve 17 and carrying the usual arms 21 having the usual governor balls 22 at their free ends. The pulley 18 is coupled to the arms 21 by links 22, as shown.

As its lower end shaft 20 is provided with a disk 23 which is rotatable with the shaft and movable therewith through the sleeve 17.

Electric contacts 24 and 25 are located above and below the disk 23 and are alternately engaged thereby as the disk is moved upwardly and downwardly under the influence of the shaft when operated by the weighted balls, as hereafter explained.

A spring contact 14 is connected to the 75 frame of the governor and is in constant contact with the disk 23 and follows the latter in its movements.

Supported in any convenient location adjacent the flow controlling mechanism 11 is 80 a frame 26 including guide members 27 and bearings 28, the latter rotatively supporting a belt pulley 29 having an internally threaded hub 30.

Slidably in the guides 27 is a cross head 85 device 31, and carried by the cross head is a bar 32 held from rotation in the cross head and threaded as shown at 33 to engage the threaded hub 30 of the belt pulley 29. By this means when the pulley 29 is rotated the bar 32 will be moved longitudinally and the cross head 31 correspondingly moved in the guideways 27. The gate actuating mechanism includes an operating member 34 pivotally connected to the bar 32 by a 90 rod 35.

Means are provided for actuating the belt pulley 29 consisting of a relatively small electrically driven motor, represented conventionally at 36, and including a shaft 37 100 having a belt pinion 38 from which a belt 39 leads over the pulley 29.

The reversing devices are connected to the contacts 24 and 25 and to the disk 23 by conductor wires indicated respectively at 105 42—43 and 41.

Means are thus provided for "setting" the gate mechanism to any required degree to permit a normal flow to the motor 10, independently of the influence of the controlling motor 36, and so long as the speed of the water driven motor is "normal" the

disk 23 will be maintained in neutral position, or out of engagement with both of the contracts 24 and 25.

If the flow through the gates of the motor 10 increases, the speed of the latter will be correspondingly increased, and the speed of the governor will also be correspondingly increased and cause the weighted arms 21 to rise and depress the shaft 20 and its disk 23, and cause the latter to engage the contact 25 and close a circuit through the disk and the motor 36, and rotate the shaft 37 in a direction to cause the threaded bar 32 to close the gates of the motor 10 and thus 15 check the flow of water and reduce the speed.

If the flow of water decreases the arms 21 will fall and elevate the shaft 20 and disk 23 and cause connection between the 20 disk and contact 24, and close a circuit through the motor 36 in reverse order and so reverse the motion of the shaft 37 and correspondingly reverse the motion of the bar 32 and open the gates of the motor 10 and 25 permit more water to flow therethrough and thus increase the speed of the water driven motor.

The motion of the motor 10 is thus automatically controlled and maintained at a uniform speed.

The preferred embodiment of the invention is disclosed in the drawings and set forth in the specifications, but it will be understood that any modifications within the scope of the claims may be made in 35 the construction without departing from the principle of the invention or sacrificing any of its advantages.

What I claim is:

In an apparatus of the class described, a 40 supporting frame, an internally threaded member mounted for rotation in said frame, guide devices in spaced relation extending from the frame, a cross head member slidably engaging said guide devices, a bar 45 rigidly coupled to said cross head member and externally threaded to engage the internally threaded member, means for rotating said internally threaded member and an operating member swingingly coupled to the 50 cross head member.

In testimony whereof, I affix my signature hereto.

HOWARD S. CRISPIN.
